TOY RAILWAY SIGNAL TOWERS

Lawrence Cowen, New York, N. Y., assignor to The Lionel Corporation, New York, N. Y., a corporation of New York

Application February 3, 1954, Serial No. 407,942

9 Claims. (Cl. 46—12)

The present invention relates to toy railway signal towers and is more particularly directed toward railway signal towers which simulate the action of a signal man moving from an observation balcony on the tower down a stairway to signal the train.

The present invention contemplates a toy signal tower adapted to be placed along the right of way of the toy railway and to be operated by remote control so as to shift a manikin from the front of the tower into the tower and another manikin from the top of the stairway down to the bottom of the stairway, and to automatically return the manikins to normal position when the remote control is released.

The present invention contemplates a tower for the above purposes having a base, a tower structure simulating a two-story building and provided with a toy stairway at the side. The building encloses the operating mechanism whereby the manikins are shifted back and forth. This mechanism is preferably spring-biased to a normal position with one manikin in an observation position in front of the tower and the other manikin at the top of the stairway, and is actuated to shift the manikins by an electromagnet controlled externally of the tower.

Other and further objects will be disclosed as the description proceeds.

The accompanying drawings show, for purposes of illustrating the present invention, one embodiment in which the invention may take form, it being understood that the drawings are illustrative of the invention rather than limiting the same.

In the accompanying drawings:

Figure 1 is a perspective view of the toy tower;

Figure 2 is a front elevational view of the toy tower with the manikins in full lines in the normal position and in dot and dash lines in the shifted position;

Figure 3 is a side elevational view of the tower with the manikins in similar positions and with parts broken away to show interior construction;

Figure 4 is a top plan view of the toy tower with the roof removed and portions of the stairway and shed about the stairway broken away to show interior construction;

Figure 5 is an inverted plan view of the toy tower;

Figure 6 is a vertical sectional view taken on the line 6—6 of Figures 4 and 5 with parts broken back to show interior construction;

Figure 7 is a fragmentary sectional view taken on the line 7—7 of Figure 4;

Figure 8 is a fragmentary section taken on the line 8—8 of Figure 7;

Figure 9 is a fragmentary section taken on the line 9—9 of Figure 7; and

Figure 10 is a fragmentary sectional view taken on the line 10—10 of Figure 4.

The toy tower has a base 10 made of plastic material and a four-sided house simulating body 11 also made of plastic material. This body member has a front lower-story doorway and door indicated at 12 and has second-

2

story glazed windows as indicated at 13. It also has at the second story level a front doorway opening 14 and horizontal floor or partition 15 at the second story floor level. The body is secured to the base by four metal rods 16a, 16b, 16c, 16d, headed at the upper ends. Certain of the rods act as electric conductors, as will be described.

A toy stairway 17 in the form of a plastic molding is mounted alongside the two-story tower unit. This stairway unit is secured in place by a projecting element 18 which passes through a hole or opening 19 in the base 10. It is securely held against lateral movement by a bar 20 received in a rectangular recess indicated at 20'. The upper end of the stairway member 17 is provided with a base or extension 21 (see Fig. 8), which passes through a hole in the side of the tower body 11 and is cemented in place. To hold the stairway away from the tower body, the stairway element is provided with a spacer indicated at 21' (Fig. 6). A shed or cover member 22, also made of plastic material, is secured to the side of the tower and about the upper end of the stairway 17. This shed or cover member 22 has prongs 23a, b, c which are passed through holes in the side of the molding 11 and snapped past the inner wall of the tower member so that the cover is securely held in place. To complete the toy building, a roof 24 is loosely supported on the top of the tower body.

The remote control operating mechanism for actuating the manikins is carried on a metal plate 25. This plate is held in place by prongs 26, 26 which, extend down through an opening 27 in the floor element 15, and by the longer 30 of the metal rods 16b. This rod 16b passes down through a rocker arm assembly indicated at R. in Figures 4, 6 and 10. The rocker arm assembly has a bracket 28 of U-shaped cross-section lying on its side. Its lower side 29 rests on the raised boss 25' of plate 25, while its upper side 30 is riveted as indicated at 30a and 30b (Fig. 4) to a rocker arm 31. A sleeve 32 passes through the rocker arm 31 and the upper side of the bracket 28 as indicated in Figure 10. The rocker arm assembly is biased to the position indicated by a spring 33 extending rearwardly and secured to an anchorage 33a carried by the rod 16c. The rocker arm 31 has a forward extension indicated at 34 which normally passes through the door opening or doorway 14 and carries the manikin 35 so that this manikin is normally in a position in front of the tower and within a balcony-forming element indicated at 36.

The extreme left end 37 of the rocker arm 31 is connected by a cord 38 which passes through an opening 39 in the side wall of the tower and is connected at its other end to a slider 40 carried by a stairway element 17. This slider is adapted to move up and down the stairway element 17 in a groove indicated at 41 (see Figs. 4 and 6). The slider 40 has a bracket-like portion 42 which carries a figure or manikin 43. This figure is normally held in the upper position by the tension of the spring 33 acting on the rocker arm assembly.

The metal plate 25 has an upwardly bent flange 50 which, together with a coil bracket member 51 supports a magnet coil 52. One end of this coil is grounded to the plate 25 and is connected through rod 16b with a spring fastener 53 which carries a wire receiving terminal 54. The other end of the coil 52 is connected by wire 55 and soldering lug 55' with the rod 16d which in turn carries a spring fastener 56 provided with wire receiving terminal 57.

The coil 52 receives an armature or plunger 58 connected by a link 59 with the rocker arm mechanism so that when the coil is energized, the rocker arm is shifted from the full line position of Figure 4 to the dotted line position. This brings the manikin 35 into the interior of the tower and allows the manikin 43 to slide down

the stairway to the dotted line position shown in Figures 2, 3 and 4. When the coil is de-energized, the spring restores the parts to the normal position. This operation simulates the movement of a tower man from the balcony in front of the tower out through the tower and down the stairway to signal the train and his return after the train has passed by.

In order to light the interior of the tower, the device is provided with a lamp 60 carried in a lamp socket 61. The socket is supported on a bracket 62 having spring fingers 63, 63 adapted to pass through an opening 64 in the plate 25. One side of the socket is grounded and the other side is connected by a lug 66 and a wire 67 with the soldering lug 67 secured to the rod 16a. This rod carries a wire receiving terminal indicated at 68 (Figure 5). The lamp is accessible for replacement through the large opening 70 formed in the base 10.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. A toy railway signal tower having a toy tower body simulating a two-story building and provided with an upwardly and rearwardly extending, external stairway and with a front doorway at the second story level, two manikins, means for supporting one manikin from the tower body for oscillatory movement back and forth through the doorway, means for supporting the other manikin for sliding movement up and down the stairway, spring means for protracting the first manikin and concurrently holding the second manikin at the top of the stairway, and electromagnetic means for retracting the first manikin and releasing the second manikin so that it may slide down along the stairway.

2. A toy tower such as claimed in claim 1, wherein the first manikin is carried on a spring biased lever and the lever is connected by a cord with the second manikin.

3. A toy tower for simulating action normally taking place on a railway signal tower, comprising a base, a tower body having a front doorway, an external stairway leading from the base to the rear of the tower body at the level of the bottom of the doorway, a first manikin pivotally secured to the body for movement through the doorway, a second manikin guided for movement up and down the stairway and gravity biased toward the bottom of the stairway, a spring biasing the first manikin out through the doorway, means operable by the spring for normally holding the second manikin at the top of the stairway, and means for shifting the first manikin into the tower body and releasing the second manikin for movement down the stairway so that when the first manikin enters the tower body the second goes down the stairway.

4. A toy tower such as claimed in claim 1, including a lever on which the first manikin is carried and to which the spring is connected, and the shifting means includes a solenoid coil connected to the lever to tension the spring.

5. A toy tower such as claimed in claim 1, wherein the tower body has a balcony simulating portion in which the first manikin is normally held by the spring.

6. A toy tower for simulating action normally taking place on a railway signal tower comprising a base, a tower body having walls simulating the appearance of a two-story railway signal tower, a second story front balcony with doorway leading thereto, an outside stairway leading from the base up to the second story level,

and a floor connecting the walls at a level substantially above the level of the base, a floor supported arm pivoted to swing about a vertical axis, a manikin carried by the arm for movement back and forth through the doorway, a spring biasing the manikin to a forward position, and a floor-carried electromagnet connected to the arm to retract the arm and manikin, a second manikin guided for movement up and down the stairway and gravity biased toward the bottom of the stairway, and a cord connecting the second manikin and the arm and acting on the second manikin to retract it up the stairway when the spring protracts the first manikin into the tower body.

7. A toy railway signal tower comprising a base, a four-sided toy tower body simulating a two-story building and having a front doorway opening at the second story level, the body having a floor member interconnecting the sides below the doorway, a plate secured to the upper face of the floor, a rocker arm pivoted to the plate near the front of the tower to one side of the doorway, a manikin carried by the rocker arm and movable back and forth through the doorway, a spring biasing the rocker arm forwardly, an electromagnet carried by the plate and connected to the rocker arm to swing it rearwardly and move the manikin into the tower body, a stairway simulating part secured to the side of the tower body adjacent the pivot and extending upwardly from the base to the rear of the tower body at the level of the second story, a second manikin guided for movement up and down the stairway and gravity biased downwardly, and a cord connecting the second manikin and the rocker arm and acting to normally hold the second manikin in its upper position.

8. A toy railway signal tower such as claimed in claim 7, wherein the tower body and base are made of insulating material, and having conducting rods which pass through the floor and base to secure the tower body onto the base, and electrical connections between two of the rods and the coil of the electromagnet.

9. A toy railway signal tower comprising a base, a one-piece plastic molded tower body having four walls simulating the side walls of a two-story building and a floor plate interconnecting the side walls at the level of the floor of the second story, the front wall having an open doorway at the second story level, metal rods headed at their upper ends and extending through the floor plate and the base, fasteners secured to the lower ends of the rods to secure the tower body to the base, an externally disposed stairway-forming member having its lower end secured to the front of the base and its upper end to the rear of one of the side walls, a metal plate secured to the upper face of the floor, a plate supported electromagnet having an armature and a coil one side of which is grounded to the plate and the other side of which is connected to one of the rods, a rocker arm assembly pivotally mounted on another rod and connected to the armature to shift the arm rearwardly, a spring acting on the rocker arm to bias it forwardly, a manikin on the rocker arm movable back and forth through the doorway, a slider guided for movement up and down the stairway, a second manikin carried by the slider, and a cord connecting the second manikin on the rocker arm assembly to raise the second manikin when the first manikin is protracted.
